UNITED STATES PATENT OFFICE.

WILLIS K. HODGMAN, OF TAUNTON, MASSACHUSETTS.

UNDER GUIDE FOR PRINTING-MACHINES.

SPECIFICATION forming part of Letters Patent No. 340,785, dated April 27, 1886.

Application filed October 19, 1885. Serial No. 180,351. (No model.)

To all whom it may concern:

Be it known that I, WILLIS K. HODGMAN, of Taunton, in the county of Bristol and State of Massachusetts, have invented a new and useful Improvement in Under Guides for Printing-Machines, which improvement or invention is fully set forth and illustrated in the following specification and accompanying drawings.

My invention relates to certain improvements in that class of printing-presses in which the impression-cylinder is a continuously-rotating cylinder and arranged to take an impression at every turn.

In all printing-presses having continuously-rotating impression-cylinders the sheet to be printed is laid upon the feed-board, its front edge being supported in position to be clamped by the cylinder-grippers by narrow pieces of sheet steel, which are fastened to and project out from the feed-board. These pieces of sheet steel are called "under guides." The free ends of the front guides rest upon the under guides and prevent the sheet from sliding onto the impression-cylinder until the proper moment, when they are raised out of the way and the sheet allowed to slide off the under guides and onto the impression-cylinder.

My invention consists of raised ribs, which encircle the impression-cylinder from about the tail end of its impression-surface to about the gripper-edge of the same, and serve to support the front edge of the sheet in a perfectly-straight line at exactly the same height as the impression-surface, thus obviating any tendency of the sheet to puff up when it is clamped over the under guides. I attain this object by the mechanism illustrated in the accompanying drawings, in which—

Figure 1 is a vertical section of a machine embodying my invention on the line xx , Fig. 2. Fig. 2 is a vertical section of the same on the line yy , Fig. 1. Fig. 3 is a plan of the machine.

Similar letters refer to similar parts throughout the several views.

A A' are the side frames, and, together with the foundation B, constitute the frame-work of the machine.

C is the impression-cylinder mounted on the shaft D.

e is the delivery-cylinder mounted on the shaft e'.

P P' are a tight and loose pulley, which, by means of the driving-shaft G³ and driving-pinion G², transfer motion to the impression-cylinder gear G, which is fastened on one end of the shaft D, and which meshes with the delivery-cylinder gear G', which is fastened on one end of the shaft e'.

F is the feed-board, and S is the sheet which is about to be taken by the impression-cylinder grippers.

g are the impression-cylinder grippers.

C' is the impression-surface, upon which the sheet S lies while being printed.

e' are the delivery-cylinder grippers, and take the sheet from the impression-cylinder grippers g and convey it to the fly-tapes t, which carry it over the fly. (Not shown.)

f are the front guides, and rock on the front-guide shaft f' sufficiently to allow the sheet S to pass under their free ends at the proper time.

f² is the front-guide lever, upon the free end of which is the roll f³, which engages with the flange-cam f⁴, (shown in dotted lines in Fig. 1,) and operates to lift the free ends of the front guides, f, at the proper time.

U are the raised ribs, which support the front edge of the sheet S before it is clamped by the grippers g.

U' are pieces bolted to the flange of the cylinder C, and serve to extend the ribs U nearer to the tail and gripper-edge of the impression-surface C'.

Operation: In Fig. 1 I have shown the machine in position when the sheet S is about to be taken by the impression-cylinder grippers g. The sheet S is supported in position to be taken by the grippers g by the raised ribs U and their extensions U', and is held from sliding onto the cylinder C before the proper time by the front guides, f, which are cut out so as to fit over the raised ribs U. (See Fig. 2.)

As the impression-cylinder C revolves in the direction shown by the arrow, the roll f³, on the free end of the lever f², comes in contact with the flange-cam f⁴, causing the free ends of the front guides, f, to lift sufficiently to allow the sheet S to pass underneath. At the same time the grippers g are closed onto the edge of the sheet S by any well-known means. (Not shown.) As the cylinder C continues to revolve, the sheet S is printed, then

taken by the delivery-cylinder grippers e^2 , and finally delivered to the fly (not shown) by the tapes t . Shortly after the tail end of the sheet S has passed under the free ends of the front guides, f , the roll f^3 comes to the end of the flange-cam f^4 , and the front guides again close over the raised ribs U , ready to hold another sheet in position.

I am aware that prior to my invention stop-cylinders have been made with under guides fastened to the cylinders, and I do not wish to be understood as laying claim to such construction; but,

Having thus fully described my invention, what I claim as new, and desire to secure by Letters Patent, is—

1. In a printing-press having a continuously-

rotating impression-cylinder, the combination, with the feed-board and front guides, of said impression-cylinder fitted with under guides 20 in the form of raised ribs, substantially as set forth.

2. The continuously - rotating impression-cylinder C , having under guides consisting of the raised ribs U , attached to its surface, and 25 extending from the gripper-edge to the tail end of the impression-surface on the opposite side of the cylinder from the impression-surface, substantially as shown, for the purpose specified.

WILLIS K. HODGMAN.
